UNITED STATES PATENT OFFICE.

MATTHIAS J. VINIK, OF NEW YORK, N. Y.

MOVING-PICTURE MACHINE.

1,254,532.

Specification of Letters Patent. Patented Jan. 22, 1918.

Application filed January 29, 1914. Serial No. 815,162.

To all whom it may concern:

Be it known that I, MATTHIAS J. VINIK, a subject of the Czar of Russia, and a resident of the city of New York, borough of Manhattan, in the county and State of New York, have invented a new and Improved Moving-Picture Machine, of which the following is a full, clear, and exact description.

10 The object of the invention is to provide a new and improved moving picture machine arranged to increase the length of time the film is at rest for the exposure of a picture and to shorten the time of the film motion when changing from one picture to the next following one to such an extent as to eliminate all flicker and to utilize a greater percentage of the arc light and to make it impossible to detect the change or the so-called "travel ghost" whether a shutter is used or not.

Another object is to feed the film through the machine by rolling contact instead of pulling it through vertical stationary guides, thus eliminating the destructive wear on the film and allowing a picture on the curved portion of the film to be correctly projected onto a flat surface.

In order to accomplish the desired result use is made of a film-feeding device having intermittently-driven rotary means at the point of exposure for feeding the film through the machine by rolling contact. Use is also made of a correcting lens at a point of exposure directly opposite the curved or segmental portion of the film projecting the picture on the curved portion of the film correctly onto a flat screen or other surface.

40 A practical embodiment of the invention is represented in the accompanying drawings forming a part of this specification, in which similar characters of reference indicate corresponding parts in all the views.

45 Figure 1 is a rear elevation of the moving picture machine;

Fig. 2 is a sectional side elevation of the same on the line 2—2 of Fig. 1;

50 Fig. 3 is a rear elevation of part of the moving picture machine with the guide rollers for the films omitted;

Fig. 4 is a side elevation of the moving picture machine;

55 Fig. 5 is an elevation of the film-feeding device, one of the wheels and its support being shown in section;

Fig. 6 is a sectional side elevation of the Geneva stop mechanism, the section being on the line 6—6 of Fig. 8;

Fig. 7 is a similar view of the same on the line 7—7 of Fig. 8;

Fig. 8 is a plan view, with parts in section, of the actuating device of the intermittent feed mechanism;

Fig. 9 is a similar view of the same with the parts in a different position;

Fig. 10 is a face view of the wheel shaft, the intermittently rotating and lengthwise-sliding shaft and the coupling connecting the said shafts with each other;

Fig. 11 is a sectional side elevation of the coupling connecting the wheel shaft and the Geneva wheel shaft with each other;

Fig. 12 is a cross section of the crank mechanism for imparting a sliding movement to the shaft of the Geneva stop wheel, the section being on the line 12—12 of Fig. 10;

Fig. 13 is a sectional side elevation of the moving picture machine on the line 13—13 of Fig. 1;

Fig. 14 is an inverted sectional plan view of a modified form of the actuating mechanism for the intermittent feeding device, the section being on the line 14—14 of Fig. 15;

Fig. 15 is a sectional side elevation of the same on the line 15—15 of Fig. 14;

Fig. 16 is a plan view of the same; and

Fig. 17 is a sectional side elevation of the same on the line 17—17 of Fig. 14.

In moving picture machines as heretofore constructed it has been found impracticable to feed the film intermittently through the machine beyond a well known speed, as otherwise the strain on the film becomes so great as to tear the film. In the machines heretofore used the ratio between the period of rest and that of the film's motion was 3 to 1 and hence the change from one picture to another produced the so-called "travel ghost" when run without a shutter, and a flicker at the screen when using the shutter.

With my improvements presently described in detail the ratio between the periods of rest and motion may be increased to 7 to 1 or 11 to 1 and even to a higher ratio without danger of injury to the film, it being obvious that at the high ratios mentioned the flicker, due to ability to cover the picture more than three times at each exposure is practically eliminated and the

"travel ghost" so reduced that the shutters in case of weak light can be dispensed with.

The moving picture machine is mounted on a suitably constructed frame A in which 5 are journaled spaced sprocket feed wheels B, B' around a portion of which passes the film C provided with the usual series of pictures. The film C is held in contact with the peripheral faces of the feed wheels B, 10 B' by the use of friction rollers D, D' journaled in the upper and lower portions of the plate E provided with an opening E' for the passage of the rays of light to the curved or segmental portion of the film held 15 at the time opposite the opening E' on the peripheral faces of the wheels B, B', as plainly indicated in Fig. 13. The rays of light are received from a condenser F and a source of light F' and immediately adjacent the inner face of the film portion or 20 picture exposed at the time to the rays of light is arranged a correcting lens G which directs the image to an objective H of usual construction, for projecting the image on 25 a distant flat screen or other similar surface. The correcting lens G has a cylindrical curvature, as indicated in Fig. 13, and corrects the blurred and distorted image owing to the curvature given to the film by 30 the wheels B, B' so that the image is correctly and sharply projected on the distant screen or surface. The correcting lens G is held in a segmental support G' which also forms a support for the body of the film 35 during its travel around the wheels B, B', and the said support G' is attached to the frame A and extends between the wheels B, B'. It is understood that the support G' follows the curvature of the wheels B, 40 B' without touching the body of the film. By reference to Fig. 13 it will be noticed that a large number of the sprockets of the wheels B and B' are in engagement at the time with a corresponding number of the 45 usual apertures in the sides of the film C so that the film C can be fed through the machine at a high speed without danger of tearing the film as the latter is in rolling contact with the peripheral faces of the 50 wheels B, B'.

In order to impart an intermittent rotary motion to the wheels B, B' at the ratios above mentioned, the following arrangement is made: On the shafts B², B³ carrying the wheels B, B' are secured gear wheels I, I' (see Figs. 3 and 5) in mesh with pinions I², I³ secured on a shaft I⁴ journaled in suitable bearings arranged on the main frame A. On the pinion I² (see Figs. 8, 9, 55 10 and 11) is secured a coupling member I⁵ provided with a slot I⁶ in which is mounted to slide a pin J' secured on a shaft J mounted to turn in suitable bearings arranged on the main frame A and adapted to slide 60 longitudinally in the said bearings. It will

be noticed that when the shaft J is turned the pin J' turns the coupling I⁵ and consequently the shaft I⁴, and the slot I⁶ is of such a length as to correspond to the lengthwise throw given to the shaft J so that the 70 pin J' remains at all times in coupling engagement with the slot I⁶ of the coupling member I⁵. On the shaft J is secured a star wheel J² forming part of a Geneva movement and adapted to be engaged by a 75 pin J³ projecting from the face of a wheel J⁴ having a hub J⁵ engaging the usual peripheral portions on the star wheel J². The wheel J⁴ is secured on a shaft J⁶ provided with a pinion K in mesh with a gear wheel K' secured on a shaft K² (see Figs. 1 and 4) journaled in suitable bearings arranged on the main frame. On the shaft K² is secured a pinion K³ in mesh with a gear wheel K⁴ secured on the main driving shaft K⁵ 80 provided with a suitable handle K⁶ under the control of the operator for turning the shaft K⁵. It will be noticed that when the shaft K⁵ is turned the train of gear wheels consisting of the gear wheel K⁴, pinion K³, 85 shaft K² and pinion K imparts a rotary motion to the shaft J⁶ thus rotating the wheel J⁴ and causing the pin J³ to engage and turn the star wheel J² whereby an intermittent rotary motion is given to the shaft J 90 and consequently to the wheels B, B' by the pinions I², I³ and the gear wheels I and I'. The star wheel J² moves alternately in and out of the path of the pin J³, and the arrangement is such that the pin wheel J⁴ 95 makes one revolution without the pin J³ engaging the star wheel J² and makes a second revolution engaging the star wheel J² to give the latter a quarter turn, it being understood that the star wheel is provided with four radial slots, as indicated in Figs. 6 and 7, thus producing a ratio of 1 to 7, or, in other words, the image on the film opposite the lens G is in motion one-seventh of the length of time the image 100 is at rest. In case a higher ratio is desired the star wheel J² is provided with three radial slots so that the ratio is 1 to 11, that is, the image on the film opposite the lens G is in motion one-eleventh of the time the 105 picture is at rest.

In order to impart a lengthwise sliding movement to the shaft J with a view to move the star wheel J² alternately in and out of the path of the pin J³, the following arrangement is made: The outer end of the shaft J is mounted to turn in a shifting collar L pivotally connected by a pitman L' with a crank pin L² held on a crank shaft L³ journaled in suitable bearings arranged on the main frame A. On the shaft L³ is secured a bevel gear wheel L⁴ in mesh with gear wheel L⁵ fastened to the shaft J⁶ so that when the latter is rotated a rotary motion is transmitted 110 by the bevel gear wheels L⁵, L⁴ to the crank 115 L³.

shaft L^3 which by the crank pin L^2 and the pitman L' and collar L imparts a sliding motion to the shaft J in the direction of the length thereof so that the star wheel J^2 in 5 one position (see Fig. 8) is in the path of the pin J^3 , and in another position, as shown in Fig. 9, the star wheel J^2 is out of the path of the pin J^3 . The hub J^5 of the pin wheel J^4 is provided with a cut-out portion J^7 for the passage of the points of the star wheel J^2 when the latter is intermittently rotated by the pin J^3 . The pivot pins L^8 of the pitman L' extend through the shifting collar L into an annular groove J^8 formed in the shaft J (see Fig. 12) so that the shaft J is free to turn in the shifting collar and the movement given to the latter causes a sliding of the shaft J in the direction of the length thereof. The shaft 10 J^6 is provided with the usual fly wheel J^9 to insure the steady running of the machine.

In order to feed the film C to the wheels B , B' and the film rollers D , D' use is made of spaced overhead sprocket wheels N , N' 15 in vertical alinement with the sprocket wheels B , B' (see Fig. 3), and the said sprocket wheels N , N' operate in conjunction with top and bottom film rollers N^2 , N^3 journaled in suitable bearings arranged in a bracket A' forming part of the main frame A . The sprocket wheels N , N' are secured on a shaft N^4 journaled in the bracket A' and on the said shaft N^4 is secured a bevel gear wheel N^5 in mesh with a bevel gear 20 wheel N^6 secured on the upper end of a shaft N^7 journaled in suitable bearings arranged on the main frame A and its bracket A' . On the lower end of the shaft N^7 is secured a bevel gear wheel N^8 in mesh with a bevel gear 25 wheel N^9 secured on the shaft K^2 previously mentioned (see Figs. 1, 2 and 4), thus when the shaft K^2 is rotated, as previously mentioned, a rotary motion is transmitted by the gearing just described 30 to the sprocket wheels N , N' to feed the film by rolling contact in a downward direction and to the sprocket wheels B , B' . It is understood that the peripheral speed of the sprocket wheels N , N' corresponds to that 35 of the sprocket wheels B , B' .

In case it is desired to use a shutter O in conjunction with the objective H such a shutter O is formed of a narrow plate or plates and is secured on a shaft O' journaled 40 in suitable bearings arranged on the main frame A . On the shaft O' is secured a bevel gear wheel O^2 in mesh with a bevel gear wheel O^3 secured on the upper end of a shaft O^4 journaled in suitable bearings arranged on the main frame A . On the lower end of the shaft O^4 is secured a bevel gear wheel O^5 in mesh with a bevel gear wheel O^6 secured on a shaft O^7 journaled in suitable bearings arranged on the main frame A . 45 On the shaft O^7 is secured a gear wheel O^8

in mesh with the gear wheel K' , previously mentioned, (see Fig. 4) so that when the gear wheel K' is rotated a rotary motion is transmitted by the gearing just described to the shutter shaft O' and the shutter O to 50 close the objective H during the period of movement of the film C . If a two-blade shutter is used with this arrangement it will cover the picture six times at each exposure against three times the highest possible up 55 to now.

In the modified form shown in Figs. 14, 15, 16 and 17, the star wheel P is secured to a shaft P' which is secured to the shaft I^4 carrying the pinions I^2 , I^3 previously 60 mentioned. The star wheel P has no sliding movement relative to the pin Q but the latter besides revolving has a sliding movement to move into and out of the path of the star wheel P . The pin Q is held to turn in a pin 65 carrier in the form of an arm Q' extending from a bar Q^2 mounted to slide in a groove R' formed lengthwise in a revolving shaft R driven from the shaft K^5 by a train of 70 gear wheels similar to the train of gear 75 wheels above described and which connects the said shaft K^5 with the shaft J^6 , as above stated. The bar Q^2 is attached to a circular head Q^3 mounted to turn in a bearing S of a sleeve S' loosely mounted on the shaft R to 80 slide thereon. The sleeve S' is provided with a pivot pin S^2 engaged by a pitman T connected with a crank pin U on the face of a bevel gear wheel U' in mesh with a pinion U^2 secured on the shaft R . Thus when the 85 latter is rotated the pitman T imparts a sliding motion to the sleeve S' whereby a sliding motion is given to the bar Q^2 and the pin Q to move the latter into and out of the path of the star wheel P . It is understood that the bar Q^2 rotates with the shaft R so that the pin Q is revolved, and the pin Q imparts a turning motion to the star 90 wheel P whenever the pin is in engagement with the star wheel P . The pin Q slides in 95 a wheel Q^4 mounted on the shaft R and having a hub Q^5 provided with an opening Q^6 adapted to be closed by a segmental shoe Q^7 attached to the bar Q^2 . Thus when the 100 pin Q moves out of the path of the star wheel P the shoe Q^7 passes into the opening Q^6 and closes the same to hold the star wheel P against turning, it being understood that the usual recesses of the star wheel are adapted to engage the peripheral face of the hub Q^5 to hold the star wheel from turning. When the pin Q moves into the path of the 105 star wheel P the shoe Q^7 moves out of the opening Q^6 to allow the corresponding point of the star wheel P to pass through the said opening at the time the star wheel P is turned by the pin Q . It will be noticed that when the machine is running a reciprocating motion is given by the crank pin U , pitman T , sleeve S' , bar Q^2 and shaft P^2 to the pin Q 110

115 120 125 130

to move the latter in and out of engagement with a corresponding slot in the star wheel P so that the star wheel is given a quarter turn during every second revolution of the shaft R. The advantage of this modification is that it permits the pin to revolve, thus increasing its life.

- By reference to Figs. 6, 7 and 15, it will be noticed that the star wheels J^2 and P have their slots tangential to the pins J^3 and Q, respectively, so that the pins correctly enter the slots and thereby turn the star wheels without jerk or jar.
- 10

By the use of the step-down pinions I^2 , I^3 in mesh with the gear wheels I and I' the wheels B, B' can be made sufficiently large to simultaneously engage a large number of sprockets of the said wheels B and B' with the film, thus permitting the rotation of the 15 wheels B, B' at a high rate of speed without danger of tearing the film.

It is understood that although I have shown and described star wheels having three and four radial slots, it is evident that 20 a star wheel with more than four slots may be used to decrease or increase the ratio of the periods of rest and movement of the film correspondingly. It is also understood that the proportional dimensions of the step-down gearing I, I', I^2 , I^3 may be varied to 25 allow an increase in the size of the wheels B, B' with a view to engage more sprockets of these wheels with the apertures at the sides of the film.

30 Having thus described my invention, I claim as new and desire to secure by Letters Patent:

1. A moving picture machine provided with spaced revoluble members arranged between a condenser and an objective and around a portion of which the film passes, means for intermittently operating the members and means for feeding the film to said members.

40 2. A moving picture machine provided with intermittently-rotating wheels spaced apart and around which passes the film, and a correcting lens for correcting the projection of the curved portion of the film.

45 3. A moving picture machine provided with feeding means for moving the film through the machine by rolling contact, and optical correcting means for correcting the

projection of the image on the curved portion of the film.

4. A moving picture machine provided with intermittently-rotating sprocket wheels spaced apart, a correcting lens between the sprocket wheels adjacent the curved portion of the film, a condenser and an objective 55 in alignment with each other and located on opposite sides of the correcting lens.

5. A moving picture machine provided with a pair of spaced feed wheels around a portion of which the film passes while passing between the condenser and objective, gear wheels for rotating the said feed wheels, a pair of pinions in mesh with the said gear wheels, an intermittent rotary mechanism for intermittently rotating the 60 said pinions, and means for feeding the film to said feed wheels.

6. In a moving picture machine, the combination with a condenser, an objective and a film feeding mechanism, of a pair of spaced wheels between the condenser and objective, means for causing the film to pass around a portion of said wheels, and means for operating the feed mechanism and the 75 said wheels intermittently and in unison.

7. A moving picture machine provided with an objective, a condenser, a pair of sprocket wheels carrying a film, the sprocket wheels being spaced apart and arranged intermediate the said condenser and objective 80 to cause the rays of light to pass between the sprocket wheels, and means for intermittently rotating the sprocket wheels.

8. In a moving picture machine, the combination with a condenser, an objective, and a support arranged between the condenser and objective and provided with an opening for the rays of light, of a pair of spaced feed wheels mounted in the support, friction rollers mounted in the upper and lower 95 portions of the support whereby to cause the film to pass around a portion of said wheels, and means for intermittently operating the feed wheels.

In testimony whereof I have signed my 100 name to this specification in the presence of two subscribing witnesses.

MATTHIAS J. VINIK.
